UNITED STATES PATENT OFFICE.

CARL REINHOLD SCHWALENBERG, OF MANNHEIM, GERMANY.

AIR-CUSHION.

SPECIFICATION forming part of Letters Patent No. 787,473, dated April 18, 1905.

Application filed November 30, 1903. Serial No. 183,258.

To all whom it may concern:

Be it known that I, CARL REINHOLD SCHWALENBERG, a subject of the Grand Duke of Baden, and a resident of 14 Heidelbergerstrasse, Mannheim, in Grand Duchy of Baden, German Empire, have invented certain new and useful Improvements in Air-Cushions, of which the following is an exact specification.

My invention relates to improvements in air-cushions manufactured of elastic india-rubber plates, and has for its purpose to provide means for avoiding that the plates lose their elasticity and form as well as their strength.

In order to make my invention more clear, I refer to the accompanying drawings, in which—

Figure 1 is partly a plan and partly a section on line A B of Fig. 2 of an air-cushion constructed according to my invention. Fig. 2 is a section of the same on line C D of Fig. 1.

In the drawings, *a* is a ring-formed india-rubber air-cushion.

b represents wedge-formed pieces of tricot fixed to the walls of the cushion. It will be understood that the wedge-shaped tricot pieces may be fixed to the inside as well as to the outside of the cushion. The purpose of this construction is the following: The walls near the inner circumference or cut-out of the air-cushion will soon get loose and baggy by the pressure exerted from outside by the person using the cushion. The cushion therefore becomes thinner as its surface around the cut-out has increased. As the inner pressure has the same amount per square inch all over the inner surface of the cushion, the specific tension upon the part around the cut-out of the cushion soon becomes greater, the result of which will be that the cushion loses its elasticity. In order to do away with this disadvantage, I arrange the pieces of tricot *b* around the cut-out of the cushion according to the figures.

It is well known that tricot can only be stretched in one direction. If one continuous piece of tricot would be cemented all around the inner circumference of the cushion, so that it can only stretch in the cross direction, the cushion would lose its elasticity in the longitudinal direction of the strip. In order

to do away with this disadvantage, wedge-shaped pieces of tricot are provided according to the present invention, which wedge-shaped pieces are cut so as to allow a stretching in the cross direction, the stretching in the longitudinal direction being allowed on account of no continuous strips of tricot, but only single pieces being arranged.

It will be understood that the wedge-shaped pieces of tricot may be arranged so that alternately one wedge-shaped piece allowing a stretching in the cross direction and another wedge-shaped piece allowing a stretching in the longitudinal direction are fixed to the rubber. It will also be understood that the whole inside or outside of the cushion may be provided with wedge-shaped pieces of tricot situated so as to allow a stretching in one or the other direction or alternately in both directions.

Having thus fully described the nature of my invention, what I desire to secure by Letters Patent of the United States is—

1. In an elastic air-cushion, the combination of a ring-shaped india-rubber cushion with wedge-shaped pieces of tricot fixed to the wall of the cushion at the inside of the ring, each of these tricot pieces allowing independently from the other pieces, a limited stretching of that cushion part to which it is cemented, substantially as described and for the purpose set forth.

2. In an elastic air-cushion, the combination of a ring-formed india-rubber cushion, with a wedge-shaped piece of tricot, fixed to the inside of the wall of the cushion at the inside of the ring, the wedge-shaped tricot pieces partly permitting a stretching of their proper cushion parts in substantially radial direction, partly allowing a stretching in substantially circumferential direction, substantially as described and for the purpose set forth.

In testimony whereof I have signed my name to this specification in the presence of two subscribing witnesses.

CARL REINHOLD SCHWALENBERG.
